UNITED STATES PATENT OFFICE.

FRANK C. MEDICK, OF COLUMBUS, OHIO.

DECKLING MACHINE.

Application filed June 30, 1924. Serial No. 723,283.

To all whom it may concern:

Be it known that I, FRANK C. MEDICK, a citizen of the United States, residing at Columbus, in the county of Franklin and State of Ohio, have invented certain new and useful Improvements in Deckling Machines, of which the following is a specification.

This invention relates to an improvement in machines for deckling the edges of photograph mounts. The main purpose of the improvement is to provide mechanism whereby a photograph mount can be fed in an improved manner through the machine and during one passage through the machine have two opposing edges deckled.

The machine is composed of duplicate parts and by that it is meant that many parts are used in different locations of the machine, which are duplicates of other parts, set in reverse position from the first mentioned parts.

In general, the machine comprises two distinct units, one of which is in a sense stationary, while the companion unit is movable in its entirety. Each unit has movable feed supporting parts, as hereinafter more fully described.

Referring to the drawings, Fig. 1 is a plan view of the machine; Fig. 2 is a right end view; Fig. 3 is a transverse section on line 3—3 of Fig. 1 (part of same being in elevation); Fig. 4 is a transverse section on line 4—4 of Fig. 1; Fig. 5 is a transverse section on line 5—5 of Fig. 1, taken through the center of the feed belts; Fig. 6 is a transverse section on line 6—6 of Fig. 5; Fig. 7 is a transverse section on line 7—7 of Fig. 5; Fig. 8 is a transverse section on line 8—8 of Fig. 5; Fig. 9 is a diagrammatic view of the transmission mechanism; Fig. 10 is a front elevation on line 10—10 of Fig. 1; Fig. 11 is a sectional view on line 11—11 of Fig. 2.

The base of the machine is indicated by 1 (Figs. 1 and 3); the motor, illustrated as a prime mover for the various moving parts, is indicated by 2; the side frame is indicated by 3 (see Fig. 2). This side frame is composed of uprights and spacers, and as indicated in Fig. 2 there are two side frames which are duplicates, one of the other, placed side by side in reverse positions; that is, one end of one side frame is placed adjacent to the opposite end of the companion

side frame. Each side frame has an end elevated to a higher plane than the other end, and in Fig. 2 the end of one side frame lying in the lower horizontal plane is shown, while the elevated end of the companion side frame is shown.

The feed mechanism support is indicated at 4 (Fig. 2) and this support is mounted to slide on the end of the frame 3 lying in the lower horizontal plane. Referring to Fig. 65 1 the feed mechanism supports carry the two sets of mechanism, one being shown at the right hand side of the figure and the other at the left side. One unit comprises the front half of the machine having the 70 feed mechanism at the right hand side, supported on the movable feed support, while the deckling devices and other parts are supported directly on the stationary frame, and the rear unit has the deckling devices supported on the elevated part of the stationary 75 frame at the right hand side of the figure. Throughout this specification the front of the machine is that part appearing in Fig. 1 as nearest the person facing the machine, it 80 being understood that the operator stands at that side of the machine and feeds the photograph mounts into the machine from the front side thereof, and the mounts are fed out of the machine at the rear part of the Fig. 1. 85

A drive shaft is indicated by 5, which is coupled to the motor shaft. This shaft is mounted in bearings 6—6 near the front of the machine as indicated in Fig. 3. The transmission devices at the left side of Fig. 90 9 consist of the shaft 5 carrying a pinion 7 secured to said shaft; pinion 7 engages with the gear 8, which is secured to the counter-shaft 9, carrying pinion 10, engaging gear 11 on shaft 13 carrying pinion 12 engaging the 95 gear 14, which is secured to a stub shaft 15, and this constitutes the transmission for the front feeding mechanism and extends from the drive shaft 5 to the feed rolls, the gear 14 (Fig. 9) being shown in engagement with pinion 16, which is secured to one of the feed rolls, hereinafter more fully described. A similar set of transmission devices for the feed mechanism of the other unit at the rear 100 end of the machine is shown at the right hand of Fig. 9 and is in all respects the same as the transmission just described. It is important in mechanism of this kind that the feed rolls of each set and the feed rolls 105 of the two sets should operate in perfect 110

synchronism, to eliminate any danger of buckling or tearing the photograph mounts during the feeding movement. The pinions 16 are shown in mesh with upper pinions 17 and the pinions 18 are shown in mesh with upper pinions 19 and these comprise the front set consisting of two pairs of pinions. The pinion 16 is secured to a lower feed roll 21 (see Fig. 5), while the pinion 17 is secured to the upper feed roll 21. The pinion 19 is secured to an upper feed roll 24, and the companion pinion 18 is secured to a feed roll 24'. As shown in Fig. 5, there are two sets of rolls and each set includes two pairs of upper and lower feed rolls. One set of these feed rolls is part of the front unit of the machine, while the other set is in the rear unit. The feed belts 25 are specially prepared for the work of carrying or feeding the photograph mounts and to this end the surfaces and edges are ground to insure perfect alignment of the parts thereof. Each set has an upper and lower feed belt and the mount is fed between the two belts. It will become apparent that when the photograph mount passes from the front feed mechanism to the rear feed mechanism there will always be danger of impairing the mount unless the feed rolls of the rear section and the feed rolls of the front section are rotated in perfect synchronism. Moreover, it is likewise important that the upper feed rolls and the lower feed rolls of each set should operate in synchronism. The rolls 22 and 23 are idlers, the function of which is to maintain the feed belt in proper alignment and sufficiently taut. The feed rolls of the two sets are the same size, besides operating in synchronism, to cause belts to have same linear velocity.

The mechanism for insuring synchronism between the feed rolls of one set and the feed rolls of the other set is shown at the lower end of Fig. 9. This comprises a sprocket chain 28 which extends over two sprocket wheels 29, which are identical in size, one with the other. One sprocket 29 is at the front part of the machine on the shaft 5, secured in any ordinary way to rotate simultaneously with said shaft, but the other sprocket on a rear drive shaft 30 (see Fig. 4) is secured with elongated hubs to rotate in a forked bearing and this sprocket 29 is keyed to that drive shaft, so that the drive shaft may slide laterally through said sprocket to take care of the sliding movement of the rear unit hereinafter more fully set forth. In this manner the two sets of transmission mechanism for the feed rolls of the front and rear units are interconnected so that the feed rolls will be positively driven in synchronism. In this connection, it is important to remember that during the passage of the photograph mount through

the machine the feeding belt of one unit engages one part of a mount and the feed belt of the other unit may engage a part of the mount somewhat removed from the first part. This will necessarily occur with some mounts of the larger sizes and the machines are intended to operate on photograph mounts of various widths, say from three inches to thirty inches. In case the feed rolls do not operate in synchronism, there will always be danger by reason of the feeding belt of one unit operating at a different velocity from the feeding belt of the other unit that the photograph mount will revolve in one direction or another, so that its edge will not be properly presented to both sets of deckling devices, it being understood that there is a set of deckling devices for each unit as hereinafter more fully set forth.

As shown in Fig. 4, the upper portion of the supporting frame for the feed rolls is adjustably mounted, so that the part of the supporting frame to which the upper feed rolls are attached can be raised and lowered to enable the operator to have access to the space between the feed rolls for the purpose of repairing parts or for any other purpose. This upper frame is raised and lowered by the wheel 31, which is secured to a screw threaded shaft and by turning this wheel 31 the frame can be raised and lowered in the usual and ordinary way as indicated in said figure. There is also shown an end-wise adjustment of the feed supporting mechanism by the wheel 32 (see also Fig. 10). The feed supporting frame 4 is shown with lugs integrally formed thereon and the wheel shaft 58 is mounted so as to rotate within said lugs, but longitudinal movement of said shaft on said support 4 is prevented by a shoulder formed on said shaft and a cap secured to the end of said shaft. Said shaft is extended through bracket 59, which is bolted to the frame 3, formed with internal threads, so that by turning the wheel 32 the feed support can be moved relatively to the frame. In this way, the operator can gain access to the space between the feed rolls by first moving the feed support in a horizontal plane so as to remove the feed belt and feed rolls from any obstructions that will prevent the upper part of the frame being elevated as heretofore explained. Thereupon, by turning the wheel 31, the upper part of the feed support can be elevated to enable the operator to have access to the space between the feed rolls, etc.

In Figs. 4 and 6 there is shown at 33 an adjusting device for the upper end idler roll of each set of rolls, to adjust same to cause the belt to have the proper tautness. This consists of a standard stud bolt and set screw so arranged as to hold the bearing in proper position to secure tension in the usual way. The feed roller 22 (Fig. 8) has

its bearing, spring pressed into position, and the shaft to which said bearing is secured has a self aligning ball bearing at its outer end and in this way the upper feed roll 22 of each set is maintained in proper alignment and maintains the two rollers in proper contact and is capable of adjustment by the operator.

The table 36 has a gauge 37 for adjusting 10 the position of the mount before it is fed into the machine and 38 is a follow board (Fig. 2) placed on the stock catcher on the rear of the machine for causing the mounts to stack up in uniform piles.

15 The belt pulley 39 (Fig. 3) is for a belt which connects the drive shaft 5 with the countershaft 40 (Fig. 1), a belt pulley 41 being secured to countershaft 40. The bearings for shaft 40 are indicated at 42—42. 20 The pulleys 43—43 and belts are to connect countershaft 40 with two deckler shafts 44 and 45 (Fig. 3). 46 and 46 (Fig. 3) are housings for said deckler shafts and the support for these housings is indicated at 25 47. The housing for the upper deckler is adjustably mounted on the support 47 in any usual and ordinary way. The plates 48—48 are arranged to form a conduit for the portion of the mount that extends beyond 30 the feed rolls and belt, and this conduit is made wide enough to accommodate the mount of maximum width.

The decklers comprise a series of disks with serrated edges (Figs. 4 and 7) indicated 35 at 49. The deckler shafts 44 and 45 (Figs. 3 and 4) are set at an inclination to the feed belts for two reasons: One reason being for convenience of location and the other reason being to distribute the work of deckling so that the first cutters will make the initial 40 cut and the others will finish the deckling. By reason of arranging the deckler shafts at an inclination to the feed belts, it is desirable 45 to arrange the front set of decklers at a point near the inner part of the machine and the rear set of decklers near the outer part of the machine, otherwise it would be difficult to locate the deckler shafts, so they 50 would not interfere with other parts of the machine.

To eliminate danger of the belts feeding 55 the mount improperly at the point where the decklers attack the edges of the mount and to overcome any tendency to tear the mount back of the edges, it is desirable to reinforce the feed belts near that point and to this end there is shown a pair of blocks 50 (Fig. 7), each having a flange portion 51. The upper block is spring pressed into engaging 60 position and is shown secured to an anchor rod 52 swiveled at its rear end. Specially hardened and polished plates 53 and 53 are secured to the flange portions 51 and these plates are maintained in parallelism 65 by the foregoing arrangement of parts,

thereby insuring that the mount will be protected from any mutilation while the edges are being deckled.

The lateral adjustment of the feed mechanism of each unit is shown in Fig. 10, where- 70 in 32 indicates the adjusting wheel, 58 is the wheel shaft which is journaled in lugs formed on the support 4. The bracket 59 is secured to the frame 3 and has internal screw threads and the wheel shaft is formed 75 with blocks or shoulders to prevent any longitudinal movement of the shaft through the lugs. Consequently, when the wheel is rotated, the support 4 will slide upon the frame 3 to enable the operator to gain access 80 to parts that need adjustment or repair.

In Fig. 11 there is shown a similar adjusting device for the entire rear unit of the machine. In Fig. 4 this rear unit is shown 85 slidingly mounted on the base 1 and in Fig. 11 the adjusting wheel 54 and shaft 55 control the movement of the rear unit. The internally screw threaded bracket 57 is secured to the base and the lugs 56 are secured to the frame, so that by turning the wheel 90 the rear unit can be caused to slide upon the base and the drive shaft 30, which is journaled on the frame, will slide through the sprocket, as heretofore explained.

Because the upper deckler and lower 95 deckler are rotated in reverse directions, one belt connecting countershaft 40 with a deckler shaft 45 is shown twisted (Fig. 1).

61 indicates a blower (Fig. 2) which is employed to remove the waste material removed from the edges of the mount by the decklers. This blower is connected to a conduit which extends to the points where each pair of decklers is located, and is driven 100 by belts and pulleys secured to shafts 5 105 and 30.

Having thus described my invention, I claim:

1. The method of deckling the edges of a flexible photograph mount by engaging the 110 body portion of the mount between two flexible surfaces, thereafter deckling the edges of the mount while same is being carried by the said surfaces and stiffening the carrying surfaces and the body portion of the mount 115 at the point where the deckling is being done.

2. The method of deckling the edges of a flexible photograph mount by engaging the 120 body portion of said mount between flexible carrying surfaces, there being two units of flexible carrying surfaces one separated from the other, the two units being synchronized to move in unison, thereafter deckling the edges on opposing sides of said carrying surfaces simultaneously, the deckling occurring at separated points on said carrying surfaces, the body portion of the mount and the carrying surfaces being stiffened at 125 the point where the deckling occurs. 130

3. In a machine of the character described, the combination of two complete units comprising feeding devices and deckling devices, the feeding devices consisting of upper and lower carrying webs and operating rolls for said webs, means for synchronizing the two units of feeding devices and for synchronizing the rolls of each unit, and deckling devices located near the edges of the webs, one deckling device being located a pre-determined distance in advance of the other.
4. In a machine of the character described, the combination of two separate units each consisting of a plurality of feeding rolls and a plurality of webs operated by said rolls, means for synchronizing the movement of the two units and for synchronizing the various rolls of each unit, deckling devices arranged on opposite sides of the web, one deckling device being located in advance of the other a pre-determined distance, and reinforcing devices placed adjacent to the points where the deckling devices operate to prevent buckling of the web.
5. In a machine of the character described, a combination of two separate units consisting of a plurality of feeding rolls and a plurality of inter-engaging carrying webs, the webs being arranged in pairs, and each pair of webs being separated one from the other, means for synchronizing the movement of the two units and for synchronizing the feeding rolls of each unit, deckling devices arranged to operate upon the edges of the article being fed, said deckling devices being placed one in advance of the other a pre-determined distance and each deckling device being arranged to operate at an inclination to the line of movement of the web.
6. In a machine of the character described the combination of two complete units comprising feeding devices and deckling devices, one unit being stationary in its relation to the vertical plane through the machine and the other unit being movable in its entirety with relation to the vertical plane of the machine.
7. In a machine of the character described the combination of two separate units consisting of a plurality of feeding devices and deckling devices, one of said units being fixed on the base and the other unit being slidably mounted on the base, means for causing last mentioned unit to slide upon said base and means for causing the feeding devices of the two units to operate in synchronism.
8. In a machine of the character described the combination of two separate units, each unit comprising a feeding device, transmission mechanism, driving device and deckling devices, one of said units being fixed on the base and the other unit movable laterally on said base, means for causing the transmission devices of the two units to operate in synchronism one with the other.
9. In a machine of the character described the combination of two units each comprising feeding devices, transmission mechanism, driving devices connected with said transmission mechanism and deckling devices, one of said units being stationarily mounted on the base and the other movably mounted for lateral movement, means for causing the two sets of transmission devices to operate in synchronism and means for causing all of the feeding devices of each unit to operate in synchronism.
10. In a machine of the character described the combination of two units each comprising a driving device, a transmission device, feeding rolls with a flexible carrying device operated by said feed rolls and deckling devices, one of said units being mounted at a fixed point and the other movably mounted, means for causing the feed rolls of the two units to operate in synchronism and means for causing the feed rolls of each unit to operate in synchronism.
11. In a machine of the character described the combination of feeding devices comprising a plurality of feeding rolls, a flexible web extending around said rolls, a transmission device connected with said feeding rolls, a driving device for said transmission device, a re-enforcing member for said flexible carrying device, consisting of parallel hardened plates in true parallelism.
12. In a machine of the character described the combination of feeding devices comprising a plurality of feeding rolls, flexible web carrying devices extending over said rolls, a transmission device connected with said rolls, a driving device connected with said transmission device, a deckling device adjacent to said web carrying device, also operated by said driving device, a re-enforcing member comprising two plates arranged to re-enforce the web carrying device at a point adjacent to the edge thereof and means for maintaining said plates in parallel relation.

In testimony whereof, I have hereunto set my hand this 19th day of June, 1924.

FRANK C. MEDICK.
